INVENTOR

UNITED STATES PATENT OFFICE.

HENRY W. GOVIN, OF NORRBORO, MASSACHUSETTS.

HINGE FOR DOORS.

Application filed March 26, 1921. Serial No. 455,962.

To all whom it may concern:

Be it known that I, HENRY W. GOVIN, a citizen of the United States, residing at Northboro, in the county of Worcester and

5 State of Massachusetts, have invented new and useful Improvements in Hinges for Doors, of which the following is a specification.

This invention relates to improvements in 10 doors and mechanism for opening and closing said doors.

One of the objects of my invention is to provide means capable of hingedly mounting and supporting either longitudinal edge 15 of a door within and upon a door frame for the purpose of assuring that the door may open to right angular position adjacent one or the other opposing sides of the door frame.

20 Another object of my invention is to provide a simple, efficient and inexpensive means of hingedly mounting a door within a door frame in such a manner as to allow the door to open from either of its opposing 25 longitudinal edges.

A still further object of my invention is to provide a door with two knob shafts arranged adjacent its opposing longitudinal edges, there being disposed upon the ends of 30 said shafts the usual knobs.

It is designed in carrying out the objects of my invention to allow an operator to turn either knob on either of the opposing longitudinal edges of the door and mounted 35 on the shafts to swing the edge of the door adjacent the knob undergoing a turning operation about the opposite side of the door frame also suitable hinges provided therefor. Similarly the operator upon turning 40 either knob at the adjacent longitudinal edge of the door opposite to the other knobs to swing this edge of the door to open position upon the hinges provided for supporting the door for this purpose.

45 A still further object of my invention is to provide a highly efficient and fool-proof door operating mechanism the parts of which are largely concealed within the door and not accessible to view and which may 50 quickly be operated by manually controlled means for hingedly seating one longitudinal edge of the door and unhinging the other longitudinal edge thereof.

Another object of my invention is to provide 55 means for locking the door so as to

render any of the four knobs which the door carries inoperative, thereby preventing the removal of the door nefariously.

With the above and other objects in view my invention consists in the combination, 60 arrangement and details of construction disclosed in the drawings and specification and then more particularly pointed out in the appended claims.

In the drawings wherein similar reference 65 characters designate similar parts throughout the respective views,

Figure 1 is a front elevation of the door,

Figure 2 is an end elevation thereof,

Figure 3 and Figure 4 are respectively 70 front and rear elevations of the door with the strips removed therefrom,

Figure 5 is a fragmental, top plan view,

Figure 6 is a bottom view of the threshold,

Figure 7 is a top plan view of the door 75 in open position,

Figure 8 is a vertical side elevation partly in section of the door with the front fac- ing removed,

Figure 9 and Figure 10 show different 80 positions of the lock mechanism on the door.

Figure 11 is an end view of the door with the strips thereon,

Figure 12 is a view showing the door fully 85 opened,

Figures 13 and 14 are front and side views of a hinge element,

Figures 15 and 16 are respectively top 90 plan and cross sectional views through Fig- ure 14,

Figure 17 is a detailed view of a locking pin,

Figure 18 is a fragmental, sectional view 95 of a locking part,

Figures 19 and 20 are respectively plan and side views of a guide, and

Figure 21 shows the parts of Figure 17 in modified position.

In the drawings which are merely illus- 100 trative of my invention, 1 designates broadly a door frame or a frame having a doorway which may be provided with parting strips 2 so as to limit the movement of the door to a closed position. 3 designates the thresh- old of the door and 4 designates the upper part of the door. The door is broadly design- nated 5 and will preferably be provided with the panel receiving openings 6.

The door is of the usual construction ex- 110

cept that it is designed to be cut away so as to form longitudinal grooves 7 and 8 upon its opposing longitudinal edges, these grooves are adapted to be closed in any suitable manner by the strips 9 of wood or of any other suitable material. The bottom strip of the threshold 3 is cut away at its opposite ends to receive the tubular keepers 10 which are imbedded flush therein, and a similar pair of tubular keepers 11 are imbedded in the upper strip or part of the door frame 4. The upper and lower sets of keepers are in vertical alinement with each other. The opposite ends of the upper and lower edges of the door 12 and 13 are cut away to provide notches 14 which communicate with the ends of the grooves 7 and 8 respectively. Extending crosswise within the keepers 11 are the pins 15 which extend as chords of these tubular keepers. These pins are disposed at right angles to the front plane of the door and are only located in the upper keepers. It will be seen that the inner planes of the grooves 7 and 8 are narrower than the upper portions thereof, thereby providing the opposing shoulders 16 and 17 extending longitudinally of said grooves.

A plurality of guide members 18 having the guide opening or passages 19 are provided with base flanges 20 which may be secured to the opposing shoulders 16 and 17 by fasteners 21 or other suitable means so that these guide members project into the narrow portions of the grooves and the base flanges project into the wider portions thereof. A pair of preferably polygonal plungers 22 and 23 are slidably guided in the members 18 in one of the grooves and another pair of plungers 24 and 25 are similarly guided. The guide members 26 are located in the ends of the grooves at the corners of the door and have the guide openings 27 in which the plungers are slidably mounted, the opposing outer ends of each plunger is round in cross section as at 28 which portions are formed with an annular groove 29, it being noticed that the shoulders 30 are thus formed having the flat sides 31, these shoulders and grooves being formed only at the upper ends of the upper plungers and the flat sides confront each other. The inner ends of the two sets of plungers are bifurcated as at 32 in which are pivotally connected links 33 the lower ends of which are attached by pivot 34 to the arms 35 of the bell crank levers 36, the latter bell crank lever being fixedly mounted upon the knob shafts 37 projecting through the opposite sides 38 and 39 of the door 5 and having secured to the opposite ends the knobs 40 in the usual manner. A transverse groove or passage 41 connects the two grooves 7 and 8 and movably extending in the groove 41 is a connecting rod or pusher 42, a pivot 43 connecting the rod 42 to the opposite arms of the bell crank levers, this pivot also connecting the links 44, the opposing ends of which links are pivotally connected at 45 to the bifurcated portions 46 of the other set of plungers 24 and 25. It will be noticed that when one of the first named arms of one bell crank lever is up the connecting rod 42 will cause the upper arm of the other bell crank lever to be down, this having the effect of causing the rounded ends of one set of plungers say 22 and 23 to be fully projected through the upper and lower edges 47 and 48 of the door while the opposite ends of the other set of plungers 24 and 25 are fully retracted within the door. And wear plates 49 are secured by fasteners 50 into the notches 14 so as to conceal the upper edges of the guides 26. It will be seen that one of the plungers say plunger 22 is formed with a notch 51, in which may shoot a plunger 52 or bolt 52 of a lock 53 controlled by a key 54 or the like. The arrangement of the fittings and parts of the plunger operating mechanism is such that it will be necessary to turn around the knob in the direction opposite to the other knob for a predeterminate distance in order to fully project two plungers and fully retract the other plungers and to turn any of these knobs in the same direction again in opposite directions to each other alternately and lesser distances in order to cause the ends of both sets of the plungers to be partially projected from the upper and lower edges 47 and 48 from the door 5 in which position the notch 51 comes opposite the plungers 52 for locking purposes, in this position of the projected ends of all of the plungers, the latter partially project into four keepers 10 and 11 secured in the door frame and as none of the plungers can move owing to the lock thus provided the door cannot be unseated.

In operation when one of the knobs of either side of the door and adjacent either longitudinal edge thereof is turned as far as it can in the proper direction crank lever connected to the knob shaft downwardly thereby causing the other arm of the bell crank lever to move upwardly which action draws together the inner bifurcated ends of the two plungers sliding in the groove in this edge of the door completely retracts the terminals of the two plungers within the door and as this bell crank lever turns in the mentioned direction it pushes back the connecting rod 42 which action raises the upper arm of the other bell crank lever and lowers the other arm thereof whereby the other set of plungers have their outer ends or terminals fully projected beyond the upper and lower edges of the door so that the annular groove 29 of these terminals register opposite the cross pin 15 secured in the upper keepers 10.

The knob which has just been turned is

still held by the operator and this edge of the door is pulled out in the usual operation of swinging the door to open position whereupon the shoulder 30 of the terminals of the 5 plungers will ride over so as to fully be supported upon the pins 15 thus serving to properly support this door in hinged relation upon the frame. It will be noticed that the front edges 55 of the opposing sides of 10 the door are cut away to provide the in-cut notches 57 for the reception of the trimmings around the knobs on one side of the door when the door is fully opened in right angular position with respect to the door frame. Similarly 15 should the other knob on the same side or other side of the door at the opposite longitudinal edge thereof be turned a proper distance the two terminals of the plungers supported by their shoulders from the pins 20 15 within the keepers in the door frame will be retracted downwardly out of the keepers into the door while the other terminals adjacent the opposite longitudinal edge of the door will project into the keepers and over 25 and therebelow and the operator holding the last named knob may pull the door open swingingly upon the last named projected plungers. The door must be closed completely and must engage the parting strips 2 30 before any of the knobs on any side of the door may be turned properly to unseat one edge of the door with respect to the other whichever it may be, if desired, however, the parting strips 2 may be removed and the 35 door 5 permitted to swing either way through the doorway in which case the usual spring operated latches may be provided for automatically latching the door in mid position where it will be fully closed.

40 By unlocking the plungers and causing their terminals to project equal distances out of the upper and lower edges of the door the latter can readily be unseated and removed from the door frame. However, 45 if a person is trying a knob at one side of the door adjacent one longitudinal edge thereof and another person is trying a knob on the other side of the door and adjacent the longitudinal edge thereof it will be found 50 impossible to unseat the door. In this event the person applying the greatest amount of pressure or turning force upon the knob he holds will prevail over the other person displaying the lesser amount of pressure and 55 power on the knob so that the knob held by the stronger person will turn permitting this edge of the door to be pulled swingingly to open position.

It will thus be seen by means of my invention either longitudinal edge of the door 60 may be readily opened by a person but both edges cannot at the same time be caused to unseat the door completely from its bear-

ings. If a person approaches the door from one side and sees a shadow through the 65 glass of the door of a person about to engage the knob on the other side, the first person would naturally step aside and take hold of the knob opposite to the one engaged by the person he confronts or he will wait 70 and let the other person open the door. This avoids one person crashing into another as is now very often done.

Numerous modifications may be resorted to in practice without departing in principle 75 from the details of construction herein disclosed.

What I desire to claim and secure by Letters Patent is:

1. A device as described consisting of a 80 door and a door frame, tubular keepers disposed in the lower threshold of the door frame, contractible springs disposed in said keepers, keepers disposed in the upper threshold of the door-frame, vertically movable plungers arranged in said door adjacent either longitudinal edge and adapted to take in and out of said keepers, and means for swingingly supporting the ends of said plungers in said keepers. 90

2. In combination a door frame, keepers carried by the upper end thereof, pins spanning said keepers, a door in said door-frame carrying vertically slidable bolts therein, the upper terminals of said bolts having reduced stems formed with a segmental head having its lower portion grooved out so as to provide under shoulders, means holding the shoulders of said bolts out of contact with said pins, and means whereby said bolt 95 shoulders may movably engage and be supported by said pins as said door swings. 100

3. In a device as described, in combination, a door frame having a pair of keepers at its upper threshold, a door carrying vertically slidable plungers adapted to be actuated to enter said keepers alternately, a pin spanning each keeper centrally, the upper terminals of said plungers being reduced and sector-shaped so as to have front flat 110 walls, said front flat walls of said plungers confronting said pin in parallel relation when said door is closed in said door frame, said reduced terminals having annular 115 grooves providing shoulders adapted, when the door and plungers turn together to ride over upon said pins to prevent the retraction of said plungers out of said keepers.

In witness whereof he has hereunto set his hand and affixed his seal this 17th day 120 of March, 1921.

HENRY W. GOVIN. [L.S.]
